Application February 5, 1951, Serial No. 209,466

2 Claims. (Cl. 120—9)

1

This invention relates to a marker specifically adapted to use in marking tires of parked vehicles.

It is generally conventional practice in police departments throughout the country to check on overtime parking by periodically marking one tire of each car parked in a particular parking zone. After an interval of time in excess of the legal parking limit in that zone, the cars therein are again checked. Any car bearing the original marking is obviously overparked. In order to mark a maximum of cars in a minimum of time, a mounted policeman, carrying an elongated chalk or crayon holder, drives past the parked cars at moderate speed marking one tire of each car as he passes.

I have now developed marking means specifically adapted for this use and which has an important feature of a resilient connection between the chalk holding portion of the marker and the handle portion. This feature is of importance because of the fairly strong impact frequently resulting from attempting to mark a tire while riding past a car on a motorcycle. By supporting the chalk resiliently with respect to the handle, chalk breakage, as a result of such impact, is minimized and the tendency for such an impact to knock the marker from the hand of the user is likewise minimized.

In one embodiment the marking means of the invention comprises an elongated handle, a collet adapted to receive and hold a length of marking chalk, and means resiliently joining the collet to the handle. In preferred practice the collet is resiliently joined to an end of the handle to extend therefrom at an angle to the longitudinal axis of the handle. This angular orientation of the collet has the obvious advantage of facilitating side marking of a tire from a position above the tire.

The term "chalk" as used herein contemplates any type of marking material such as conventional chalk, wax marking sticks and the like. The type of marking medium employed in the apparatus of the invention forms no part of the invention apart from the fact that such medium must be used to impart utility to the apparatus.

The invention will be clearly understood from the following detailed description taken in conjunction with the accompanying drawing in which:

Fig. 1 is an elevation view of one form of the invention;

Fig. 2 is a section taken on the line 2—2 of Fig. 1;

2

Fig. 3 is a section taken on the line 3—3 of Fig. 2;

Fig. 4 is a section of an alternative form of the apparatus taken on a plane generally at right angles to the plane of Fig. 3; and

Fig. 5 is a partial perspective view showing an alternative means for resiliently connecting the marker collet to the marker handle.

Referring to Figs. 1 to 3, the embodiment of the invention there shown comprises an elongated handle 10 conveniently having a rubberized hand grip 11 affixed at one end and a collet 14 joined to the handle 10 to project therefrom at an angle from the longitudinal axis of the handle. The preferred manner of joining the collet 14 to the handle 10 is shown in Figs. 1 and 2 and comprises a pair of square sectioned coil springs 16, 17, each spring having extending end sections embedded respectively in the adjoining ends of the handle 10 and the collet 14.

Conveniently the adjoining ends of the handle and collet are drilled to receive the ends of the two springs 16 and 17. In Fig. 2 collet 14 is shown to have a pair of receiving holes 20, 21 extending inwardly from an end face of the collet. Set screws 24, 25 are set in the collet 14 adjacent the spring receiving end to clamp the inserted ends of springs 16, 17 in the receiving holes 20, 21 respectively. The set screws are each positioned on an elongated chord of the circular section of the collet rather than on a diameter thereof to achieve the necessary purchase to hold the springs in the collet and to avoid weakening of the collet, as might result from both set screws being mounted on the same diameter or on a shorter chord. The opposite ends of springs 16 and 17 are similarly held in the end of handle 10, one of the corresponding set screws 27 being apparent in Fig. 1.

The collet itself may take several forms, a preferred form being shown in Fig. 3 as constituting a section taken on the line 3—3 of Fig. 2 and an alternative form being shown in Fig. 4 through a section perpendicular to the section of Fig. 3. Referring to Fig. 3, collet 14 there shown comprises a cylindrical body 30 having an enlarged elongated bore 31 extending from one end with the tubular portion of the body as formed by the bore being split by a plurality of evenly spaced grooves, one of the grooves 32 being visible in Fig. 3. Each of the grooves is relieved at its inner end by a hole through the body wall, the hole 33 associated with groove 32 being visible in Fig. 3. The body 30 is threaded externally at 34 adjacent the open

end thereof with the tip of the tubular portion of the body being beveled and designated in the drawing as 30B. A nut 36 is internally threaded to screw onto the threads 34 in the body and is beveled internally at its outer end to engage against the beveled tip 30B of the body. With the nut 36 backed away from the body, a length 38 of marking chalk shown in phantom in the figure may be inserted into the collet. The chalk is clamped therein by tightening up the nut 36 to exert a pressure through the adjoining beveled surfaces of the nut and collet, binding the chalk in the collet.

The alternative form of collet as shown in Fig. 4 likewise includes a body 43 having an enlarged cylindrical bore 42 throughout a major portion of its length. The body walls of the surrounding bore are, as in the foregoing embodiment, provided with diametrically opposite slots 43, 44 terminating at their inner ends at relieving holes 43A, 44A, respectively. Slotting of the body in this manner provides a flexibility necessary to clamp the chalk in the collet. In this embodiment the opposite end of the body 43 is provided with a tapered pipe thread 46, and an associated collet nut 48 is threaded internally to engage the thread 46. Clamping action on the chalk (chalk 50 shown in phantom) is determined by the degree to which the nut 48 is screwed onto the body 43.

Conveniently the collets, either of the type shown in Fig. 3 or of the type shown in Fig. 4, are made of tubular stock with the spring receiving end being plugged for purposes of rigidity and for receiving the spring ends. The manner in which the particular collet is constructed is a matter of choice and forms no part of the present invention.

An alternative form of joining a collet of the types shown in either Figs. 3 or 4 to the type of handle shown in Fig. 1 is shown in the partial perspective view of Fig. 5. In this figure a handle 60 is joined to a collet 62 by means of a single relatively broad leaf spring 64, the adjoining ends of the handle and collet respectively being slotted to receive the opposite ends of the leaf spring 64. Set screws 65, 66 in the handle 60 and collet 62, respectively, serve to hold the embedded ends to the leaf spring therein.

Various methods of resiliently joining the collet to the handle have been experimented with.

To date the two means shown in the accompanying drawing are by far the most satisfactory with the square sectioned spring being considerably superior to the leaf spring as shown in Fig. 5. A circular sectioned coil spring is entirely unsatisfactory as not being sufficiently rugged in comparison to the square sectioned spring, as illustrated, to withstand the repeated jarring accompanying use of the marker for the purpose for which it was designed.

I claim:

1. Marking means comprising an elongated handle, a collet adapted to hold a length of marking chalk, a pair of square sectioned coil springs, means anchoring one end of each spring in an end of said handle and means anchoring the other end of each spring in an end of the collet, each spring traversing in excess of one loop about an axis normal to the longitudinal axes of the handle and collet so that the collet lies at an angle and points away from the longitudinal axis of the handle.

2. Marking means comprising an elongated handle, a collet adapted to hold a length of marking chalk, a square sectioned coil spring, means anchoring one end of the spring in an end of the handle and means anchoring the other end of the spring in an end of the collet, the spring traversing in excess of one loop about an axis normal to the longitudinal axes of the handle and collet so that the collet lies at an angle to and points away from the longitudinal axis of the handle.
